UNITED STATES PATENT OFFICE.

HOWARD K. KING, OF PHILADELPHIA, PENNSYLVANIA, ASSIGNOR TO THE CHAMBERS BROTHERS COMPANY, OF SAME PLACE.

PAPER-FOLDING MACHINE.

SPECIFICATION forming part of Letters Patent No. 602,990, dated April 26, 1898.

Application filed May 1, 1897. Serial No. 634,726. (No model.)

To all whom it may concern:

Be it known that I, HOWARD K. KING, a citizen of the United States, residing in the city and county of Philadelphia, in the State of Pennsylvania, have invented certain new and useful Improvements in Paper-Folding Machines, of which the following is a full, clear, and exact description, reference being had to the accompanying drawings, of which—

10 Figure 1, Sheet 1, is a front elevation of a paper-folding machine to which my invention is applied, only such parts as are necessary to illustrate my invention being shown. Fig. 2, Sheet 2, is a side elevation, partially broken away, of Fig. 1. Fig. 3 is a detail, partly in section, showing the devices for raising and lowering the forward ends of the packing-troughs. Fig. 4, Sheet 3, is a plan view showing the shoo-fly tables and their supplemental bar as relatively arranged. Fig. 5 is a vertical section on line xx , Fig. 2, looking toward the rear end of the machine, showing means for raising and lowering the rear ends of the packing-troughs. Fig. 6 is a detail in 25 plan showing the arm extending from the rear end of one of the packing-troughs with its pivotal connection to the nut carried by the vertical threaded shaft.

This invention relates more especially to 30 paper-folding machines wherein each sheet of paper fed into the machine is divided and finally folded into several signatures—as, for example, three signatures of twelve pages each or four of sixteen each—and wherein the 35 signatures as they come from the last sets of folding-rolls are delivered to the respective packing-troughs by means of “shoo-flies.”

One object of the invention is to provide 40 means whereby the several packing-troughs can be simultaneously adjusted vertically at one end and also means whereby the other ends may also be simultaneously vertically adjusted, which latter adjustment can also be made whatever may be the position to which 45 the troughs are laterally adjusted.

Another object of the invention is to provide 45 a means whereby the shoo-flies with tables of a given size are better capable of use than heretofore with sheets of both small and 50 large sizes, without requiring any change in the shoo-flies.

The exact nature of the invention will clearly appear from the following description of a folding-machine of the said class in which my improvements are embodied, the improvements being particularly pointed out in the claims.

Referring to the accompanying drawings, which illustrate my invention, but show only those well-known parts of a three-twelfths 60 folding-machine which are necessary to an understanding of my improvements, 1 is the main frame of the machine.

2 are the last sets of folding-rollers, three in number in this instance. (Indicated by dotted lines in Fig. 1.)

4 are the usual reciprocative blades that tuck the sheets into the bite of the said rolls, which blades are carried by the vibrating arms 5.

6 are the shoo-fly boxes, and 7 their tables, upon which the edge of the sheets temporarily rest as they fall from the bite of the folding-rolls into the said boxes. Each set of the said rolls is journaled in and their folding-blade, 75 &c., is connected to a frame 8, Fig. 1, which frames are supported by and adapted to slide longitudinally upon transverse guide-rails 9, secured to the sides of the main frame, each of said frames in the present instance being secured to and resting upon its bed-plate 8^a, Fig. 2, the frames not being shown in that figure. Two of these frames, the first and second on the left, are adjusted along the said guide-rails by means of a rotatable screw- 80 threaded shaft 10, that passes through threaded holes in the frames 8. The relative pitches of the parts 10^a and 10^b of the threads of the shaft which engage the said two frames, respectively, are such that when said shaft is 85 rotated by turning a hand-wheel 11, Fig. 1, on its end in either direction the distance between the first and second frames and that between the second and the third frames, which latter is not adjustable, will be equal— 90 that is to say, the pitches of the thread are such that the first frame will when the shaft is turned travel twice the distance that the second frame travels.

The foregoing-described constructions are 100 not, however, new.

12 are the packing-troughs, of usual form,

located, respectively, below the sets of folding-rolls and shoo-flies and running in lines parallel with the rolls, respectively. The front or outer end of each of these troughs is supported by a fish-tail bracket 13, the first two of which brackets on the left constitute, in effect, nuts upon a shaft 14, which is parallel with the shaft 10 and is provided with screw-threads 14^a and 14^b, that have the same relative pitches as the threaded portions 10^a 10^b of the shaft 10. Shaft 14 is journaled in a box or bearing 15 on the end of an arm or hanger 16, hereinafter referred to. The third bracket, which supports the third packing-trough on the right, is, like the third one of the frames 8, not longitudinally adjustable, (although both said bracket and frame may be made adjustable if necessary,) while all three of the brackets rest upon the top of a common guide-bar 17. The latter is pivotally suspended by means of apertured lugs 19 at each end—to the said box 15 at one end and at the other end to a pin 20, (indicated by dotted lines,) projecting inwardly from a hanger 16^a, 25 similar to the aforesaid hanger 16, and these hangers are respectively pivoted on studs or pins 21, projecting inwardly from the sides of the main frame of the machine. The threaded shafts 10 and 14 are connected 30 by a sprocket-chain 22 or the like running over wheels 23 of the same diameter on the respective shafts.

It will be obvious that if the hangers be 35 swung on their pivots in the arc of a circle the threaded shaft 14, with the fish-tail brackets thereon, as also the third or non-adjustable bracket and the bar 17, will as a whole (and consequently the ends of the packing-troughs) be raised or lowered, as the case 40 may be. It will be equally obvious that by turning the hand-wheel on the end of the shaft 10 the first two of the frames 8 and the corresponding brackets will be moved or adjusted in concert, be the extent of the elevation 45 of the hangers and their connections what they may. In order, however, to conveniently effect the desired adjustment of the hangers and their described adjuncts, I employ the following construction:

50 24 are two screw-threaded shafts, one for each hanger, that are journaled in crowns of yokes 25, which are pivoted on a transverse horizontal shaft 27. On the lower end of each shaft 24 is a bevel-gear 28, whose teeth engage those of a similar gear 29 upon the shaft 27. This shaft is journaled in lugs 30 of the main frame. Each of the screw-threaded shafts 24 passes through a threaded nut 31, which has an inwardly-projecting pin or stud 55 32, that is pivotally attached to the hanger. The shafts 24 are substantially at right angles to the curved faces of the latter, as seen in Fig. 2. By rotating one of the shafts by turning a hand-wheel 33 thereon the other shaft 60 65 will be similarly rotated, and thus the hangers and the parts carried thereby may be swung

on their pivots to a higher or lower position and so the height of the front ends of the packing-troughs always simultaneously adjusted. 70

The rear or inner ends of the packing-troughs are pivotally supported by a part of the frames 8, so that the front end may rise or fall, and also so that both ends of the troughs will be carried together when the transverse adjustments are made by turning the hand-wheel 11 upon the shaft 10. It is or may be, however, and usually is, necessary to adjust the height of the inner ends of the packing-troughs simultaneously. This I do as follows: I secure to the rear end of each trough an arm 34, whose free end is pivoted on studs 35 of a nut 36 upon a vertical screw-threaded shaft 37, whose upper end is journaled in a lug 38, which is secured to an arm 39, that depends from the frame 8. The lower part of this shaft is journaled in a horizontal limb of an angular bracket 40, that is secured to and forms a part of the aforesaid depending arm 39. Upon the lower end of the shaft 37 is a bevel-gear 41, that engages a bevel-gear 42 upon a horizontal shaft 43, which is journaled in boxes 44 of the vertical limbs of the several brackets 40. The two bevel-gears upon the said shaft, which are connected with the adjustable frames 8, are secured to their shaft by a spline and groove, so that the gears may slide along the shaft. The third gear on the right may also, if desired, be connected to the shaft in the same way. Thus when the frames 8, &c., are adjusted the threaded shafts 37 and their adjuncts will likewise be adjusted, the gears upon said shafts always remaining engaged with the gears upon the horizontal shaft 43. By turning the hand-wheel 45 on the end of the latter shaft the several threaded shafts 37 will be rotated, and the nuts 36 carried up or down thereon, as the case may be, and consequently elevating the inner ends of the packing-troughs, which, it will be remembered, are pivotally connected to the respective nuts, and thus these ends of the troughs will at one and the same time be adjusted as may be necessary. 90 95 100 105 110 115

As it is sometimes desirable to provide means for tightening the sprocket-chain, I make the hangers 16 16^a in two parts, the outer end portion being provided with a longitudinal slot 46, Fig. 2, through which and a hole in the other part passes a bolt 47, with a nut 48 thereon that connects the two parts together. 120

The last feature of my invention to be described, which has been hereinbefore referred to, relating to the shoo-fly, has for its object to obviate a difficulty which I found to exist in practice in a folding-machine of the nature described, wherein the mechanism is adjustable to fold sheets of different sizes. This difficulty was that it was necessary to change the size of the tables of the shoo-flies within certain limits to suit the sizes of the sheets, 125 130

as if the tables were small (and they must be limited in size in such adjustable machines) they would not properly support the sheets as they descended from the folding-rolls into 5 the transfer-box—that is to say, the sheets would be liable to tip over and fall. To obviate this, I make the tables 7 of a size suitable for the smaller sheets which the machine may be adjusted to fold, and a suitable distance back of the tables I place a transverse bar 49, whose ends are secured to the main frame of the machine and whose top surface is on the same plane as that of the top surface of the several shoo-fly tables. Thus the 10 edge of the folded sheets that projects beyond the table is supported, as indicated by the dotted lines representing the sheet 50 in Figs. 2 and 4, while when the transfer-box rotates to carry the sheet into position for it to descend into the packing-trough there will be a 15 free passage-way between the table and the said bar.

Having thus described my invention, I claim as new and desire to secure by Letters 20 Patent—

1. The combination of the sliding frames carrying the folding devices, the screw-threaded shaft for laterally adjusting said frames, a second similar threaded shaft, the 25 pivoted hangers in which the latter shaft is journaled, the nut-brackets upon said shaft, the packing-troughs whose outer ends are supported by said brackets respectively, and whose inner ends are pivotally connected to 30 said frames; means for adjusting said hangers in the arc of a circle; means for supporting and vertically adjusting the inner ends of the troughs together with the sprocket-chain or the like, connecting said screw-threaded shafts, whereby the said frames and 35 packing-troughs may be adjusted laterally in concert, and the latter may be adjusted ver-

tically at any lateral adjustments thereof, substantially as and for the purpose set forth.

2. In a folding-machine of the nature described, the combination of the sliding frames carrying the folding devices, the packing-troughs, means for laterally adjusting said frames and troughs in concert, simultaneously; means for supporting, and simultaneously adjusting the elevation of, the outer ends of the troughs, and means for supporting and adjusting the elevation of the rear or inner ends of said troughs, at any lateral adjustment thereof; said latter means consisting of the vertical screw-threaded shafts connected to the said sliding frames, the nuts on the said shafts respectively, to which nuts the ends of the troughs are pivoted; the horizontally-extending shaft, and the gear connections of said vertical shafts and horizontal shaft, all constructed, combined and adapted to operate substantially as and for the purpose set forth.

3. In a folding-machine of the class recited, the combination of the sliding frames, carrying the folding devices, the shoo-flys connected to said frames, respectively, the packing-troughs; means for supporting and adjusting said frames and adjuncts with 65 relation to each other, and means for supporting and correspondingly adjusting said troughs, together with the bar adjacent to the shoo-fly tables and having its top in the same horizontal plane as that of the said tables, 70 substantially as and for the purpose specified.

In testimony whereof I have hereunto affixed my signature in the presence of two subscribing witnesses.

HOWARD K. KING.
